UNITED STATES PATENT OFFICE.

GUSTAVE F. KOLB, OF MOUNT VERNON, NEW YORK, ASSIGNOR TO THE MAUSER MANUFACTURING CO., OF NEW YORK, N. Y., A CORPORATION OF WEST VIRGINIA.

MATCH-BOX.

No. 894,837.

Specification of Letters Patent.

Patented Aug. 4, 1908.

Application filed May 18, 1907. Serial No. 374,513.

To all whom it may concern:

Be it known that I, GUSTAVE F. KOLB, a citizen of the United States, residing at Mount Vernon, Westchester county, State of New York, have invented new and useful Improvements in Match-Boxes, of which the following is a specification.

This invention relates to a match box more particularly adapted for holding small packages of semi-detached matches. The construction of the box is such that the matches are thoroughly protected from dust, &c., and that accidental ignition is prevented.

In the accompanying drawing: Figure 1 is a top view of my improved match box showing it closed; Fig. 2 an end view thereof; Fig. 3 a section on line 3--3, Fig. 1; Fig. 4 a perspective view of the box showing it open, and Fig. 5 a detail section through the hinge.

The box is provided with a flat bottom 10 which is turned upwards at the back as at 11, the curvature being substantially quadrantal in cross section. The box is further provided with a front 12, and with tapering sides 13 that extend with their rear end above the upper edge of curved back 11. The flat cover 14 is curved downwards at the back as at 15, and is provided at each side with a circular lug 16, such lugs flanking the curved extension 15 and projecting beyond the lower edge thereof. The cover is connected to the box by pivots 17 that pass through lugs 16 and sides 13. The correlation of the parts is such, that the curved extension 15 of the cover is concentric to the curved back 11 of

the box, and that it overlaps the same, whether the box is open or closed. In this way dust is effectively excluded and any sharp edges, which might cause accidental ignition of the matches, are avoided.

To simplify the construction and obtain a neat finish, it is preferred to make the pivots 17 tubular, (Fig. 5), and to upset their inner and outer ends against sides 13 and lugs 16 respectively.

I claim:

A pocket match box comprising a body having its sides at one end rounded and the adjacent portion of the bottom curved to conform to and engaging said rounded ends, a cover having one end curved concentric to and movable over the rounded portion of the bottom, ears connected to said cover at its curved end and bearing over the rounded ends of said body sides, the rounded portion of the cover having slidable engagement with the rounded portion of the bottom and adapted to limit the outward swing of the cover, and independent pivots extending through said ears and sides concentric to the curved portions of the body and cover and terminating at the inner side faces of the sides of the body, whereby the interior of the box is free of openings and projections.

Signed by me at Mount Vernon N. Y. this 16th day of May, 1907:

GUSTAVE F. KOLB.
